EXCESS-VOLTAGE PROTECTIVE
STRUCTURE

Ralph R. Pittman, Pine Bluff, Ark.

Application January 11, 1934, Serial No. 706,170

13 Claims. (CL 175—30)

This invention relates generally to excess-voltage protective devices for use with high voltage alternating current electrical systems, and has for its principal object the provision of means for positively preventing an excessive superimposed voltage rise on a conductor or connected apparatus, such as might be caused by lightning.

It is a particular object to provide a novel arrangement for the purpose of effecting the cascade flashover of a series arrangement of spark gaps formed by a plurality of normally insulated conducting electrodes supported in spaced relation.

A further object is the provision of a novel means for reducing the time lag of flashover of such a series arrangement.

A further object is the provision in an arc extinguishing device embodying one of the spark gaps of such a series arrangement, of means for reducing the rate of recovery voltage rise, thereby facilitating the extinguishment of the arc.

A further object is to provide means for reducing the voltage stress normally imposed on the insulating members of the arc extinguishing device to prevent thermal damage to such members from creepage current.

A yet further object is the provision in an arc extinguishing device of the expulsion type, of a novel discharge path providing a low initial breakdown voltage, and an arc path which may subsequently be taken by an arc following spark-over which varies both in length and cross-sectional area, the latter quantities being so related under all conditions as to effect arc extinguishment.

With the above and other objects in view which will appear from the description, my invention resides in a novel electrostatic field control arrangement, in combination with a novel type of arc extinguishing device in which is embodied certain members which assist in arc extinguishment, and at the same time effect the desired electrostatic field control, thus making possible the attainment of the desired results with a minimum of parts, and greatly simplifying the structure.

In the drawings:

Figure 1 illustrates an assembly of one embodiment of the structure, shown in perspective.

Figure 2 is a diagram of a curve showing a volt-time characteristic of my structure, in comparison with similar characteristics of certain well-known types of protective gaps.

Figure 3 is an elevation of the arc extinguishing device, shown in section.

Figure 4 is another view of the arc extinguishing device, as seen from the plane indicated by the line 4—4 in Figure 3.

Figure 5 is an additional view of the arc extinguishing device, as seen from the plane indicated by the line 5—5 in Figure 3.

Figure 6 is a fragmentary plan view of the mounting base of the arc extinguishing device, illustrating the venting means.

Figure 7 is a perspective of the cylindroid forming the upper electrode of the arc extinguishing device.

Figure 8 is an elevational view of another embodiment of the invention, shown partly in section.

Figure 9 is an elevational view of yet another embodiment of the invention, also shown partly in section.

Referring now in detail to the embodiment of the invention illustrated in Figure 1, a portion of a usual type of steel substation supporting framework, comprising the steel members 35, 36, and 37 is designated in its entirety by the numeral 10. In accordance with usual practice, this framework is maintained at substantially ground potential, and is here shown connected to the ground 58. An insulating member, or bus support, which may be an assembly of several insulating units, is designated by 11, and extends in a downwardly direction from the steel member 37, being attached thereto at its upper end in any suitable manner, as by the cap screws 38. An upper conducting member 17, here shown as a metal ring is rigidly supported in coaxial relation with the insulating member 11, by means of a pair of outwardly and downwardly extending metal arms 28, having their respective ends attached to the ring 17 by the bolts 16, and to the lower end of the insulating member 11 by the bolts 14. One of the bolts 14 also provides a means for connecting a line conductor 13 to the lower end of the insulating member 11.

A conducting electrode 20, here shown as a metal rod, is also supported in any suitable manner at the lower end of the insulating member 11, and extends downwardly therefrom coaxially with the ring 17 and the insulating member 11.

From the above description it will be apparent that both the ring 17 and the electrode 20 are at the same potential as the conductor 13. For reasons which will later appear, the diameter of the ring 17 should be large in comparison to the diameter of the electrode 20.

A second conducting member, as the metal 55

ring 18, of substantially the same size as the ring 17, is rigidly supported in coaxial spaced relation therewith by means of the metal arm 22, the latter having its respective ends attached to the ring 18 by the bolt 23, and to the steel framework member 36 by the bolts 24. Since the supporting framework is maintained at substantially ground potential, it will be apparent that the voltage of the conductor with respect to ground potential is definitely limited to the value determined by the spacing of the rings 17 and 18.

An arc extinguishing device, for convenience designated in its entirety in Figure 1 by the numeral 12, and shown more in detail in Figures 3, 4, 5, 6 and 7, is supported coaxially with the electrode 20 by means of the flange 33, which may be attached by means of cooperating threads to the lower end of the device 12, and the bolts 34 cooperating with the flange 33 and the conducting member 35.

The arc extinguishing device 12, as shown in Fig. 3, and later described more in detail, includes the upper electrode 29 and the lower electrode 32, which are normally insulated from each other, and means for extinguishing an arc which may occur therebetween. At the upper end of the arc extinguishing device 12, and electrically connected to the upper electrode 29 of the device, is rigidly attached, by means of the bolts 25, a pair of downwardly and outwardly extending metal arms 26, at the respective ends of which, and in coaxial spaced relation with the rings 17 and 18, and the arc extinguishing device 12, is supported, by means of the bolts 27, a third conducting member or metal ring 19. The latter is substantially the same size as the rings 17 and 18. An electrode 21, here shown as a metal rod, is carried in any suitable manner at the upper end of the arc extinguishing device 12, and extends coaxially in an upward direction toward but in spaced relation with the electrode 20, to form a spark gap therebetween. From the above description, it will be apparent that the ring 19, the electrode 21, and the upper electrode 29 of the arc extinguishing device 12 are at the same potential. It will also be apparent that the ring 19 is normally at neither line potential, as is the ring 17, nor at ground potential, as is the ring 18.

The structure above described embodies two spark paths in parallel circuit relation from line conductor to ground; the first between the line conducting member or ring 17 and the ground conducting member or ring 18, and the second from the electrode 20 to the electrode 21, and thence through the arc extinguishing device 12 to the grounded member 35.

Assuming now that a high voltage with respect to ground potential is impressed upon the conductor 13, it will be apparent that the distribution of the resultant electrostatic field between the rings 17 and 18 will retard the formation of streamers from the electrodes 20 and 21, thus reducing the time lag of flashover therebetween. It will also be seen that all of the flux passing from the electrode 20 to the electrode 21 is further divided between the rings 18 and 19, and the upper electrode 29 and the lower electrode 32 of the arc extinguishing device 12. The result is a concentration of the flux between the electrodes 20 and 21 in comparison with that between the upper and lower electrodes of the arc extinguishing device 12, thereby causing cascading of the two gaps in series arrangement

from line to ground, one of which is embodied in the arc extinguishing device 12. As the voltage division between the two above-mentioned series gaps is dependent upon the relative flux division, or the relative shunt capacitance of the gaps, it will be seen that the voltage required to sparkover the series arrangement may be made substantially equal to that required to sparkover the longer of the two gaps. The spacing between the rings 17 and 18 must therefore be somewhat greater than the electrode spacing of the longer of the two series gaps, but may be made substantially less than the sum of the spacings of the electrodes forming the series arrangement.

It will be seen that the ring 17 cooperates with the ring 18 to provide a capacitance in shunt relation with the series arrangement of the gaps from line to ground formed by the electrodes 20 and 21, and 29 and 32, and that the ring 19 cooperates with the ring 18 to provide additional capacity means in shunt relation with the last named gap.

The spacing of the rings 17 and 18 in practice is preferably determined by the insulation strength of the apparatus to be protected, thus providing a definite coordination gap having a desirable volt-time characteristic. The spacing of the electrodes forming the series arrangement to ground may then be adjusted to prevent sparkover of the coordination gap, since the series arrangement embodies the arc extinguishing device for preventing a circuit outage which would occur should the coordination gap spark-over.

The volt-time characteristic of the invention is better illustrated by Figure 2, in which the line *a* may represent the volt-time breakdown characteristic of an electrical apparatus to be protected. The line *b* represents the characteristic of the above-mentioned coordination gap formed by the spaced rings 17 and 18, the slope of the line being determined by the physical dimensions of the rings employed, and it is thereby adjusted to lie below and substantially parallel to the characteristic of the apparatus to be protected. The line *c* of the protective structure, due to the novel arrangement of the conducting members, may be adjusted to flashover at substantially less voltage than either the apparatus or the coordination gap for those time intervals 50 characteristic of the rate of voltage application due to natural lightning; that is, the characteristic of the protective structure in which is embodied the arc extinguishing device lies below and substantially parallel to that of the apparatus and coordination gap to be protected.

The lines *d* and *e* of Figure 2 represent respectively the characteristics of ring-ring and rod-rod gaps which have an electrode separation equal to the sum of the electrode spacings of 60 series gaps embodied in the invention. It is apparent that neither of these gaps offers desirable protection to the connected apparatus, not only because the voltage required to cause sparkover is much higher than that of the protective arrangement herein disclosed, but also because such gaps are not inherently self-extinguishing.

The arc extinguishing device illustrated in Figures 3, 4, 5, 6, and 7 will now be described in detail. A tubular housing 38, of suitable insulating material, is supported with its principal axis normal to the metal mounting member 35, and is provided at its lower end with the metal flange 33. The bolts 34 extend through the flange 33 and the mounting member 35 to provide 75

means for rigidly supporting the housing 30. The metal cap 15 may be conveniently attached to the upper end of the housing 30 by means of cooperating threads on the respective members, 5 and entirely closes the upper end of the housing 30. A tapped hole extending downwardly from the top at the midpoint of the cap 15 and coaxial with the housing 30, together with cooperating threads on the lower end of the spark gap electrode 21 provides a convenient means for rigidly 10 mounting the latter on the upper end of the device. An additional pair of tapped holes 58 in the cap 15, located laterally of the electrode 21, are provided for receiving the cap screws 25, 15 shown in Fig. 1.

Eccentrically disposed within the housing 30, and slidably supported with its base resting on the member 35, is the hollow tubular insulating element 31, having its upper end completely closed 20 by an integral portion thereof, and open at its lower end. The inner surface of the element 31 is provided with a conducting coating 32, which is preferably of a relatively high resistance as compared to an equivalent section of copper. The 25 coating may be in the form of a conducting graphite or metallic paint, or any convenient material having the desired resistance characteristic. In addition to covering the entire inner surface of the element 31, the conducting coating 30 extends over the lower end of the wall of the element 31, to provide a lower electrode for the device. The coating 32, being in contact with the supporting member 35, is thereby maintained at substantially ground potential.

35 A hollow metal cylindroid 29, better shown in Figure 7, closed at the top and open at the bottom, is closely fitted over the top of the element 31, in such a manner that it extends downwardly from the top for a portion of the length of the element 31 and closely engages the top and outer surface thereof. The outer surface of the cylindroid 29 is aligned with the outer surface of the element 31, so that a continuous smooth external surface is provided on the assembly comprising 40 these parts. The top of the cylindroid 29 is held in engagement with the upper end of the element 31 by means of the resilient conducting member 44, the latter being positioned between the cap 15 and the cylindroid 29. The resilient conducting member 44 also serves to electrically connect these 45 parts, to the end that the cylindroid 29 is maintained at substantially the same potential as the cap 15 and the electrode 21.

The cylindroid 29, in cooperation with the 50 conducting coating 32, provide respectively the upper and lower electrodes of the arc extinguishing device, and are so spaced longitudinally of the housing 30 that the weakest electrical path is internally of the housing 30, and along the inner wall thereof.

The wall of the housing 30 is provided with a 55 pair of openings, into each of which is fitted the hollow metal cylinders 41, a flange being provided adjacent one end of each of the cylinders for engaging the inner surface of the housing 30. The purpose of the cylinders 41 is to provide a mounting for a resilient biasing means adapted to urge the element in a lateral direction in abutting relation with the inner surface of the housing 30. The cylinders 41 are conveniently located adjacent 60 the respective ends of the housing 30, and in a vertical plane passing through the lowermost point of the cylindroid 29 and the major axis of the housing 30. The metal caps 43 are fixed to outwardly extending portions of the cylinders 41

by means of cooperating threads on the respective members. The coil springs 42, each having one end thereof engaging the caps 43, and the other ends engaging the slidable members 40, are housed within the cylinders 41, and the slidable members 40 engage the outer surface of the element 31 to resiliently urge it in a lateral direction so that it engages in abutting relation the inner surface of the housing 30 along a vertical line passing through the lowermost point of the cylindroid 29. 10

From the above description it will be seen that the shortest path through the device, and therefore the one of lowest dielectric strength, will be along a line extending vertically from the lowermost point of the cylindroid or upper electrode 29 to the conducting coating or lower electrode 32, and in a space between the inner surface of the housing 30 and the outer surface of the element 31. It will also be seen that the pressure resulting from an arc following this path will be the highest per unit length of path, since this is the path of maximum arc restriction. The pressure incident to an arc over this path urges the member 31 in a lateral direction, this motion being opposed by the springs 42. Following such a movement, the arc may follow any path from the upper electrode 29 to the lower electrode 32, but, due to the novel arrangement of the electrodes, 20 as the restriction of the arc becomes less as it 25 moves around the periphery of the element 31, the length of the arc becomes correspondingly greater. The device is in this manner arranged to extinguish the arc regardless of the path taken between the electrodes. Obviously the advantage 30 of the arrangement lies in the fact that the device is adapted to sparkover at a very much lower initial voltage than would be possible in a device having an arc path of constant arc length and constant cross-sectional area of arc path, this result being accomplished without sacrifice of arc-extinguishing qualities. In addition, the impact resulting from the operation of the device, due to the resilient mounting of the element 31, is much less than that attending the operation of a 35 rigid structure of the same arc-extinguishing effectiveness.

The housing 30 and the element 31 are preferably constructed of some material which will evolve gas in the presence of an arc, as hard fiber, 40 since the device depends for its arc-extinguishing qualities upon the pressure resulting from an arc within the device. The vents 38 in the mounting member 35, as shown in Figure 6, are provided to relieve the stress due to such pressure, 45 and the circumferential reinforcing bands 39, located between the ends of the housing 30, are desirable for providing additional wall strength to enable the device to withstand the heavy pressures attending the interruption of large currents. 50

The hard fiber, mentioned specifically above as a suitable material for use in constructing the housing 30 and the element 31, is, in common with numerous other insulating materials of organic base, quite susceptible to damage from creepage currents, particularly if subjected to high voltages for long periods of time. To prevent such damage, the structure embodies means for normally impressing substantially all the 55 voltage between the electrodes 29 and 21, and in addition provides means for preventing the concentration within the housing of any flux entering the arc extinguishing device.

To further increase the arc-extinguishing qual- 60

5 ities of the device, the inner coating 32, cooperating with the cylindroid 29, with the insulating wall of the element 31 interposed therebetween, forms a capacitance in shunt relation to the voltage 10 tending to maintain the arc within the device. In an alternating current arc, the current passes through zero twice each cycle, and the recovery voltage tending to maintain the arc increases as a transient voltage at a rate determined by the 15 constants of the circuit of which the arc is a part. Obviously any capacity in shunt relation to the arc must be charged before the transient recovery voltage tending to sustain the arc can increase. A small capacitance in shunt circuit relation with 20 the arc has therefore considerable effect in reducing the rate of recovery voltage, and any such reduction assists in arc-extinguishment. It is desirable, however, that such a capacitance be so arranged and of such design that in discharging it will not set up voltage oscillations of such magnitude as to defeat its purpose. For this reason, the coating 32 is preferably of a sufficiently high resistance to provide the required damping effect to suppress such oscillations.

25 It will be seen from the above description that the important considerations in applying the device for operation on a circuit having a given normal voltage are (1) the weakest electrical path must be internally of the housing 30, and in the 30 space between the housing and the element 31, and (2) the length of any path between the upper electrode 29 and the lower electrode 32 must be sufficient that, under the conditions of operation, the normal circuit voltage will be incapable 35 of sustaining an arc over any path within the housing.

40 Additional embodiments of the invention herein described are illustrated in Figures 8 and 9, in each of which has been incorporated the above described advantages over prior art structures.

45 Referring in detail to Figure 8, it will be seen that the structure here illustrated is similar in many respects to that shown in Figure 1, the essential difference being the substitution of a dielectric material having a greater dielectric permittivity than air for accomplishing a further distribution of the flux passing between the electrodes 20 and 21.

50 The ground ring 18 in the embodiment shown by Figure 8 is supported by a plurality of pairs of insulating units. Each unit includes the porcelain body 45 having rigidly secured in insulated relation the conducting metal cap 55 and the conducting base member 46 at the respective 55 ends thereof. The bolts 48, extending through the base member 46 and the framework member 35, rigidly secure the lower unit of each pair on either side of the arc extinguishing device 12. The clip angles 50, together with the cap screws 51 co- 60 operating with the caps 55 of the upper units, and the bolts 52 cooperating with the ring 18, are provided for rigidly attaching the latter at the top of each pair of units. The ring 18 in this embodiment is maintained at ground potential by 65 the conducting member 22, the respective ends of which are attached to the framework 10 by the bolts 24, and to the clip angle 50 by the bolt 51. The cap screws 47 extend through the base members 46 of each upper unit, and into the caps 55 70 of each lower unit, rigidly connecting the two units of each pair together. One end of each of the conducting members 49 is fixed to the base member 46 of each upper unit, and the cap 55 of each lower unit by means of the cap screws 47, 75 and the other end is attached to the cap 15 of the

arc extinguishing device 12 by the cap screws 25.

It will now be seen that any flux passing from the electrode 20 to the electrode 21 is divided, in accordance with the respective permittivities of the various multiple paths, through the dielectric of the four insulating units in parallel, and in addition, as in each of the other embodiments herein described, through the dielectric of the element 31 between the cylindroid 29 and the conducting coating 32. As a result, the flux longitudinally of the arc path of the arc extinguishing device 12 is much less than that passing between the air-spaced electrodes 20 and 21, thus providing the unbalance of voltage desired across the 10 respective series gaps from electrode 20 to the 15 grounded member 35 through the arc extinguishing device.

15 Figure 9 illustrates a somewhat similar construction, in which the capacity means incorporated within the arc extinguishing device, as 20 above described, provides the means for preventing that flux passing between the electrodes 20 and 21 from concentrating between the upper and lower electrodes of the arc extinguishing device 12. In this structure the ground ring 18 25 is supported by means of a pair of outwardly and upwardly extending conducting arms 54, the lower ends of which are attached to the flange 33 by the bolts 34, and the upper ends to the ring 18 by means of the bolts 53. In this arrangement, it will be seen that the ground ring 18 is 30 so positioned in the electrostatic field of the structure as to intercept substantially all of the flux which would otherwise pass from the upper ring 17 to the cap 15 of the arc extinguishing device, thereby effectively preventing any flux entering the device 12 except that passing between the electrodes 20 and 21.

35 From the several embodiments of my invention herein described, other equivalent arrangements will be readily apparent, and it is to be understood that the invention herein disclosed is to be limited only as is necessitated by the prior art and the appended claims.

40 What I claim as new, and desire to secure by Letters Patent, is:

45 1. An excess-voltage protective arrangement adapted to be interposed between a conductor and ground, comprising a pair of conducting members rigidly supported in spaced-apart relation, one of said members being electrically connected to said conductor and the other of said members being electrically connected to ground, said pair of members forming a gap adapted to 50 definitely limit the potential difference between conductor and ground, and means for preventing flashover between said members, said means including a plurality of normally insulated conducting electrodes supported in spaced relation to provide a plurality of spark gaps in series 55 relation between said conductor and ground and capacity means including said conducting members associated with said electrodes for causing cascade flashover of said spark gaps.

60 2. An excess-voltage protective arrangement adapted to be interposed between a conductor and ground, comprising a pair of conducting members rigidly supported in spaced-apart relation at a definite distance one from the other, one of said members being electrically connected to said conductor and the other of said members being electrically connected to ground, said pair of members forming a spark gap adapted to limit 65 to a predetermined value the potential difference between said conductor and ground, and 70

- means for preventing flashover between said members, said means including a plurality of normally insulated conducting electrodes rigidly supported in spaced relation to provide a plurality of spark gaps in series circuit relation between said conductor and ground and capacity means including said conducting members associated with said electrodes for causing cascade flashover of said spark gaps, the said definite distance being less than the sum of the electrode spacings of said plurality of spark gaps.
3. In an excess-voltage protective structure subject to a voltage from a conductor to ground, insulating means supporting a plurality of normally insulated conducting electrodes to provide a first spark gap and a second spark gap in series relation from conductor to ground, a hollow insulator housing said second spark gap, and flux control means combined with said electrodes for simultaneously reducing the time lag of flashover of said gaps and impressing prior to breakdown of said gaps substantially all of said voltage on said first spark gap.
4. In an excess-voltage protective structure, means supporting a plurality of normally insulated conducting electrodes providing a plurality of spark gaps in series relation from conductor to ground, a hollow tubular insulator having gas evolving wall material therein housing an upper and a lower conducting electrode associated with said insulator to provide one of said spark gaps, the relationship between said upper and lower electrodes being such as to cause spark-over therebetween to occur within said insulator, means for venting said insulator, means for connecting said lower electrode to ground, and capacity means including said upper and lower electrodes disposed within said hollow insulator, a grounded conducting member, and means for supporting said conducting member at such a position in the electrostatic field of said structure as to restrict the entrance of flux to said capacity means except through said upper electrode.
5. In an excess voltage structure having a plurality of spark gaps in series circuit relation from conductor to ground, a hollow tubular insulator having gas evolving wall material therein, an upper and a lower conducting electrode associated with said insulator to form one of said spark gaps, structural means for causing sparkover between said electrodes to occur within said insulator to provide an enclosed spark gap, means for venting said insulator, means for maintaining said lower electrode at substantially ground potential and capacity means electrically connected in shunt relation with said enclosed spark gap, said capacity means including a grounded metal shield supported at such a position in the electrostatic field as to prevent the concentration of flux between the electrodes of said enclosed gap.
6. In an excess-voltage protective structure subject to a voltage from conductor to ground, insulating means supporting normally insulated conducting electrodes in spaced relation to provide a first spark gap and a second spark gap in series relation from conductor to ground, a hollow insulator comprising insulating material within said insulator subject to thermal damage from creepage current, structural means for causing sparkover of said second gap to occur within said insulator, and flux control means including a conducting shield at ground potential associated with said structure for reducing both the time lag of sparkover of said structure and the normal voltage gradient across said second gap, whereby damage to said insulating material due to said creepage current is prevented.
7. An arc extinguishing device comprising a first hollow insulator, upper and lower conducting electrodes at the respective ends thereof, said electrodes being so arranged with respect to said hollow insulator as to cause sparkover between said electrodes to occur within said first hollow insulator, a second hollow insulator supported within said first hollow insulator, means for increasing the capacity of the device including an integral portion of said lower electrode disposed within said second hollow insulator to provide a condenser comprising said upper electrode and said integral portion of said lower electrode with the wall of said second hollow insulator interposed therebetween, said integral portion of said lower electrode having a relatively high resistance adapted to suppress voltage oscillations resulting from a discharge between said electrodes.
8. An arc extinguishing device comprising a tubular insulator closed at the upper end and open at the lower end, a cylindrical element of insulating material within said insulator, means supporting said element of insulating material in lateral abutting engagement with said insulator, a first conducting electrode carried by said element and extending downwardly from the closed end of said insulator and a second conducting electrode positioned adjacent the open end of said insulator, said electrodes being normally insulated from each other and so related that the shortest path therebetween is along the line of abutment of said element of insulating material with the inner surface of said tubular insulator.
9. An arc extinguishing device comprising a hollow tube of insulating material having at least one end open, a substantially cylindrical element of insulating material having a diameter less than the internal diameter of said tube within in said tube to provide a single annular space, means holding said element of insulating material in lateral abutting relation with said tube, and conducting electrodes spaced apart to provide a preferential spark path therebetween internally of said tube and normally insulated from each other, said electrodes being so arranged that the weakest electrical path therebetween is along the line of abutment of said element of insulating material with said hollow tube, at least one of said electrodes being positioned in said annular space.
10. An arc extinguishing device comprising a tubular insulator closed at the upper end and open at the lower end, an element of insulating material eccentrically supported in lateral abutting engagement with the inner surface of said insulator, a first conducting electrode carried by said element and extending downwardly from the closed end of said insulator and a second conducting electrode positioned in spaced relation with said first electrode, the arrangement of said electrodes being such that the weakest electrical path therebetween is along the line of abutment between said insulator and said insulating element, and resilient means opposing the movement of said element in a lateral direction away from said weakest electrical path.
11. An arc extinguishing device comprising a tubular insulator closed at the upper end and open at the lower end, an element of insulat-

ing material eccentrically supported in lateral abutting engagement with the inner surface of said insulator, a first conducting electrode carried by said element and extending downwardly from the closed end of said insulator and a second conducting electrode positioned in spaced relationship with said first electrode, the arrangement of said electrodes being such that the weakest electrical path therebetween is along the line of abutment between said insulator and said insulating element, and resilient means arranged to continuously bias said element of insulating material toward said weakest electrical path.

10 15. An arc extinguishing device comprising a tubular insulator closed at the upper end and open at the lower end, a cylindrical element of insulating material within said insulator, means supporting said element of insulating material in lateral abutting engagement with said insulator, a first conducting electrode carried by said element and extending downwardly from the closed end of said insulator and a second conducting electrode positioned adjacent the open

end of said insulator, said electrodes being normally insulated from each other and so related that the shortest path therebetween is along the line of abutment of said element of insulating material with the inner surface of said tubular insulator, and means including an integral portion of one of said electrodes disposed within said cylindrical element of insulating material for increasing the electrical capacity of the device.
